UNITED STATES PATENT OFFICE.

GEORGE S. PIERSON, OF KALAMAZOO, MICHIGAN.

CARBURETER.

1,072,492.

Specification of Letters Patent.

Patented Sept. 9, 1913.

Application filed November 9, 1909, Serial No. 527,062. Renewed July 28, 1913. Serial No. 781,667.

To all whom it may concern:

Be it known that I, GEORGE S. PIERSON, a citizen of the United States, residing at Kalamazoo, county of Kalamazoo, Michigan, have invented certain new and useful Improvements in Carbureters, of which the following is a specification.

This invention relates to improvements in carbureters.

10 My present invention is an adaptation of, and in some respects, an improvement upon the structure of my Patent No. 898,920, dated Sept. 15, 1908.

The main objects of this invention are: 15 First, to provide in a carbureter an improved means for controlling the relative proportions of air and fuel. Second, to provide in a carbureter an improved means by which air and the fuel control members are simultaneously operated. Third, to provide 20 in a carbureter an improved structure which is very simple and not likely to get out of repair in use.

Further objects, and objects relating to 25 structural details will definitely appear from the detailed description to follow.

I accomplish the objects of my invention by the devices and means described in the following specification.

30 The structure described constitutes one effective embodiment of my invention. Other embodiments would be readily devised by those skilled in the art.

The invention is clearly defined and 35 pointed out in the claims.

A structure constituting an effective and preferred embodiment of the features of my invention is clearly illustrated in the accompanying drawing, forming a part of this 40 specification, in which:

Figure 1 is a vertical section through a structure embodying the features of my invention taken on a line corresponding to line 1-1 of Fig. 2. Fig. 2 is a plan view with 45 a portion of the body broken away to show structural details. Fig. 3 is a detail vertical section taken on a line corresponding to line 3-3 of Fig. 1. Fig. 4 is a detail vertical section corresponding to that of Fig. 3 of a 50 modified construction. Fig. 5 is a plan view of the structure shown in Fig. 4, the parts of the body or frame being broken away. Fig. 6 is a detail horizontal section, through 55 the mixing chamber, showing the mixing chamber valves completely open. Fig. 7 is a corresponding view showing the mixing

chamber valves partially closed. Fig. 8 is an enlarged detail vertical section, showing details of the fuel control valve. Fig. 9 is a detail vertical section of a modified form 60 of the fuel control valve.

In the drawings, the sectional views are taken looking in the direction of the little arrows at the ends of the section lines, and similar reference numerals refer to similar 65 parts throughout the several views.

Referring to the drawing, the mixing chamber 1 is preferably passage-like in form, and is provided with an inlet passage 2 and a discharge passage 3, the discharge 70 passage being adapted to be connected to an explosion engine cylinder.

The body 4 is preferably a casting having the mixing chamber and passages formed therein. Depending from and opening into 75 the mixing chamber 1 is a well 5 through which the fuel is fed to the mixing chamber. This well depends into the liquid reservoir 6, which is connected to a suitable source of fuel supply, as through the passage 7. The 80 passage 7 is controlled by a valve 8 and the float 9 to which the valve is connected. The details of this valve, and its connection to the float, form no part of the present invention, as they are fully disclosed in my patent 85 before referred to.

The reservoir 6 is connected to the feed well 5 by a passage 10. The fuel delivery is controlled by the valve or member 11 which depends into the well. This valve is provided with an air passage 12, discharging into the well. The discharge openings 13 for the passage 12 are arranged to deliver above the seat engaging portion of the valve 11, the discharge openings 13 being preferably laterally disposed, as clearly appears in Fig. 8. The air is delivered through the passage 12 into the well, and thence into the mixing chamber, independently of the air inlet passage 2 of the mixing chamber. 100

I preferably provide the mixing chamber with an inlet valve 14 and discharge valve 15. These valves are, in the structure illustrated, formed integrally with the valve member 16, which, in the structure shown in Fig. 1, is threaded into the body 4 of the mixing chamber to be rotated and thus operate the valves 14 and 15 simultaneously. The valves 14 and 15 and the valve member 16 are formed of a cylindrical block having 110 a transverse cut in its inner end to form the valves.

The valves 14 and 15 are preferably so arranged that the delivery passage, or discharge opening, of the mixing chamber is restricted relative to its inlet opening. This 5 secures a better suction of air through the fuel valve passage than would be the case were the inlet and aspirating openings of the same capacity. The valve 11 is preferably threaded through the valve operating 10 member 16 to be adjusted therein, a lock nut 18 being provided for securing the valve in its adjusted position. I preferably provide an index for the fuel valve. By thus arranging the parts, the inlet and discharge 15 valves of the mixing chamber are simultaneously operated, as is also the fuel valve. The air inlet valve is preferably cut off at one edge, as shown in Figs. 6 and 7, so that when the valves are partially open, the discharge 20 is somewhat restricted relative to the inlet, as clearly appears from the diagrammatic illustration of Fig. 7. When the valves are fully open, as in Fig. 6, there is no such restriction, but it is found that 25 ordinarily the carbureter is operative with the valves partially closed.

In the modified structure shown in Fig. 4, the valve operating member is not threaded into the body or frame of the carbureter, 30 but is rotatably mounted therein and held yieldingly in position by means of the spring member 20. The fuel control valve is threaded through the member 16, so that, as the member is operated to control the air 35 valves, the fuel valve is operated. A lever 21 is provided for operating the member 16. This may be connected to be operated through any desired connections.

To take up the slack in the threads I preferably provide the structure shown in Figs. 40 1 and 2 with springs 23 which are arranged to engage the valve member 16. The fuel control member in the embodiment shown in Fig. 4 is prevented from turning as the member 16 is adjusted by the spring 24 which engages the finger piece 22. The finger piece 22 for the valve 11 is preferably provided with an index for indicating the adjustment of the fuel valve. In the modified structure shown in Fig. 9 the fuel control valve or member is of the form shown in my patent hereinbefore referred to.

In my improved carbureter, I am enabled to very accurately control the proportions of 55 fuel and air and thus maintain a very proper proportion of mixture. The parts are economical to construct and assemble. The valves are, in the structure illustrated, all directly mounted on the operating member, 60 the air valves being formed integrally therewith.

I have illustrated my improvements in detail in the form in which I have embodied them in practice. I am, however, aware 65 that they are capable of considerable varia-

tion in structural details without departing from my invention, and I desire to be understood as claiming the same specifically as well as broadly.

Having thus described my invention, what I claim as new and desire to secure by Letters Patent is:

1. In a carbureter, the combination with the body having a mixing chamber therein; a fuel feed well opening into said mixing chamber; a movable valve member; a valve for said mixing chamber carried by said member; and a fuel control valve having an air supply passage therein adapted to deliver air to said well independently of said mixing chamber, said fuel valve being threaded into said valve member. 75 80

2. In a carbureter, the combination with the body having a mixing chamber therein; a fuel feed well opening into said mixing chamber; a movable valve member; a valve for said mixing chamber carried by said member; and a fuel control valve having an air supply passage therein adapted to deliver air to said well independently of said mixing chamber, said fuel valve being adjustably mounted on said valve member. 85 90

3. In a carbureter, the combination of a mixing chamber; a fuel feed well opening into said mixing chamber; a valve for said mixing chamber; and a fuel control valve having an air supply passage therein adapted to deliver air to said well independently of said mixing chamber, the discharge of 95 100 said passage in said valve being above the seat engaging portion thereof, said fuel valve being operatively connected to said mixing chamber valve.

4. In a carbureter, the combination of a mixing chamber; a fuel feed well opening 105 into said mixing chamber; a valve for said mixing chamber; and a fuel control valve having an air supply passage therein adapted to deliver air to said well independently 110 of said mixing chamber, said fuel valve being operatively connected to said mixing chamber valve. 110

5. In a carbureter, the combination of a mixing chamber; a fuel feed well opening into said mixing chamber; a valve operating member; inlet and discharge valves for said mixing chamber carried by said member whereby they are simultaneously operated, the discharge valve being arranged so that the discharge of said mixing chamber 115 is restricted relative to its inlet; and an air delivery member having an air passage 120 therein adapted to deliver to said feed well independently of said mixing chamber, said air delivery member being adjustably arranged in said valve operating member. 125

6. In a carbureter, the combination of a mixing chamber; a fuel feed well opening into said mixing chamber; a valve operating member; inlet and discharge valves for 130

said mixing chamber carried by said member whereby they are simultaneously operated, the discharge valve being arranged so that the discharge of said mixing chamber 5 is restricted relative to its inlet; and a member having an air supply passage therein adapted to deliver to said well independently of said mixing chambers, carried by said valve operating member, all coacting 10 as specified.

7. In a carbureter, the combination of a mixing chamber; a fuel feed well opening into said mixing chamber; a valve for said mixing chamber; and a member having an 15 air supply passage therein adapted to deliver to said well independently of said mixing chamber, said member being operatively connected to said mixing chamber valve and adjustably associated therewith.

20 8. In a carbureter, the combination of a mixing chamber; a fuel feed well opening into said mixing chamber; a valve for said mixing chamber; and a member having an air supply passage therein adapted to de-

liver to said well independently of said mixing chamber, said member being operatively connected to said valve for said mixing chamber.

9. In a carbureter, the combination with the mixing chamber; a fuel feed well opening into said mixing chamber; a fuel control valve having an air passage therein discharging into said well independently of said mixing chamber; inlet and discharge valves for said mixing passage; and a common member for operating said valves whereby they are simultaneously operated, said fuel valve being operatively connected to said member and being adjustably associated therewith.

15 In witness whereof, I have hereunto set my hand and seal in the presence of two witnesses.

GEORGE S. PIERSON. [L. S.]
